UNITED STATES PATENT OFFICE.

HARRY S. FLANEGIN, OF POTTSVILLE, PENNSYLVANIA, ASSIGNOR TO THE EASTERN STEEL COMPANY, OF POTTSVILLE, PENNSYLVANIA, A CORPORATION OF PENNSYLVANIA.

PULVERIZED-FUEL BURNER.

1,289,144.

Specification of Letters Patent. Patented Dec. 31, 1918.

Application filed May 15, 1918. Serial No. 97,666.

To all whom it may concern:

Be it known that I, HARRY S. FLANEGIN, a citizen of the United States, and resident of Pottsville, in the county of Schuylkill and State of Pennsylvania, have invented a new and useful Improvement in Pulverized-Fuel Burners; and I do hereby declare the following to be a full, clear, and exact description thereof.

10 My invention relates to a pulverized fuel feeder.

The object of my invention is to provide a feeder of this character, which is simple in construction, and which provides for the 15 automatical feeding of pulverized fuel from a supply-bin to be injected under high pressure in a uniform, continuous feed, and adapted to be readily adjusted to different positions so that the blast can be directed to 20 any given point in the furnace. A further object of my invention is to provide for the prevention of the coal from spreading too 25 much, thereby making a sharper flame and causing a more intense heat in a confined locality to cut or melt down the steel, where the device is used in a steel-melting furnace.

To these ends my invention consists, generally stated, in a coal-bin for containing the pulverized coal, with a pipe leading therefrom to a vacuum-chamber, a nozzle through which air under high pressure is forced, thereby creating a partial vacuum in said chamber, and by suction drawing the pulverized coal from the bin and forcing it 35 through the suitable pipe to the furnace, together with other features all as hereinafter fully set forth and claimed.

In the drawing, the numeral 2 designates the front wall of a suitable furnace, such as 40 an open-hearth furnace, having the inlet 3 for the discharge of the pulverized fuel. Supported in front of the furnace is the trolley track 4, which supports the trolley 5 with the wheels 6 traveling on said track. 45 The swivel pin 7 is connected to the trolley, and said swivel pin supports the vacuum-chamber 8. This vacuum-chamber is connected up by the flexible pipe 9 to the lower end 10 of the coal-bin 11. This bin contains 50 the pulverized coal or other fuel, and the fuel fed in the top moves down to the contracted end-portion 10, from whence it is drawn off by the pipe 9.

Extending within the vacuum-chamber 8

is the nozzle 12, which is connected up by the 55 elbow 13 with the air-supply pipe 14, controlled by the valve 15. This pipe 14 is connected up with an air compressor so that air under high pressure is delivered by the pipe 14 to the nozzle 12.

A coupling 16 connects the vacuum-chamber 8 up with the delivery pipe 17, which extends a suitable distance to bring it into proper relation with the furnace opening 3.

A coupling 18 connects the coupling 16 60 with the outer auxiliary injecting pipe 19 surrounding the pipe 17, said pipe 19 preferably extending slightly beyond the pipe 17. This, however, is not essential as the only requirement is that the delivery pipe 70 does not extend beyond the surrounding pipe. Air-supply pipe 20 for admitting air at any desired pressure is connected up to the coupling 18, and air is injected by said pipe 20 into the space between the pipes 17 75 and 19.

In the operation of the device, when the device has been properly adjusted with reference to the opening 3, the air is turned on by opening the valve 15 the proper amount, 80 and the air injected through the nozzle 12 creates a partial vacuum in the vacuum-chamber 8, and this creates a suction in the pipe 9 so that the pulverized fuel is drawn from the contracted end 10 of the bin and 85 delivered to the vacuum-chamber 8, whence it passes into the pipe 17 and is forced forward by the air at any desired pressure issuing from the nozzle 12. At the same time, air is admitted by the pipe 20 to the pipe 19, 90 and this air surrounding the fuel injected from the pipe 17 tends to confine the coal and prevent it from spreading, thereby giving a more concentrated flame and causing a more intense heat in a confined locality to 95 cut or melt down the steel. The auxiliary injecting pipe 19 admits air for discharging the fuel into the furnace, the air for combustion purposes being supplied by a separate flue. Owing to the flexibility of the 100 pipe 9 and the swivel 7, the device is quickly and readily moved to direct the blast to any given point, and the trolley permits of the burner being moved in and out.

By the above apparatus, therefore, I provide a pulverized fuel feeder adapted to inject the fuel by high pressure injection-air and, at the same time, the secondary inje-

tion-air surrounds the injected fuel, and prevents it from spreading unduly. Furthermore, by my improved fuel feeder, I obtain a uniform, continuous feed so that the heat is maintained without sudden fluctuations and, consequently, there is a saving in time and fuel.

It is apparent that by adjusting the valve 15, the quantity of coal fed to the furnace 10 may be varied.

What I claim is:

1. In a fuel burner, in combination with a receptacle for containing pulverized fuel and a vacuum chamber provided with a discharge pipe in communication therewith, of an auxiliary pipe carrying injection air surrounding said delivery pipe approximately its entire length, a carrier adapted to move in approximately horizontal plane, and 20 means to secure said carrier and said vacuum

chamber in swivel relation, substantially as described.

2. In a fuel burner, in combination with a receptacle for containing pulverized fuel and a vacuum chamber provided with a discharge pipe in communication therewith, of an auxiliary pipe carrying injection air and surrounding said delivery pipe approximately its entire length, a carrier adapted to move in an approximately horizontal plane, 30 means to secure said carrier and said vacuum chamber in swivel relation, and a controlling means for controlling the vacuum in said chamber, substantially as described.

In testimony whereof, I the said HARRY 35 S. FLANEGIN have hereunto set my hand.

HARRY S. FLANEGIN.
